(57) **CLAIM**

The ornamental design for a shoe bag, as shown and described.

DESCRIPTION

FIG. 1 is a perspective view showing the shoe bag of my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a front view thereof with the front flap opened;

FIG. 9 is a top view thereof with zipper open and front flap up;

FIG. 10 is a top view thereof with zipper closed and front flap up;

FIG. 11 is a front view thereof with the rear flap opened;

FIG. 12 is a rear view thereof with the rear flap opened;

FIG. 13 is a left side view with the flaps up; and,

FIG. 14 is a perspective view of the divider insert with hook and pile fastener tabs.

The elements shown in phantom lines do not form any part of the claimed design of the present invention.
